UNITED STATES PATENT OFFICE

JOHN S. RAYNOR, OF HOLMESBURG, PENNSYLVANIA

CLIP FOR FASTENING FORAMINOUS PLASTER KEY

Application filed July 30, 1930. Serial No. 471,641.

My invention relates to new and useful improvements in a clip for fastening foraminous plaster key, such as expanded metal, woven wire or other open mesh lathing 5 against furrings or supports and has for one of its objects to provide an exceedingly simple and effective device of this character which utilizes the resiliency or flexibility of the lathing to hold parts of the clips in position, said inherent resiliency of the lathing permitting assembly of the clip on the work.

Another object of the invention is to provide a clip of the character herein described 15 with a locking leg to prevent rotation thereof on furrings, studs or supports of small cross sectional area.

A further object of the invention is to provide a socket open at one end for the reception of the body of an adjacent or coacting clip, the open end of said socket lying toward the lathing whereby entrance thereto is restricted due to the relative position and flexibility of the lathing.

With these ends in view this invention consists in the details of construction and combination of elements hereinafter set forth and then specifically designated by the claims.

In order that those skilled in the art to which this invention appertains may understand how to make and use the same, I will describe its construction in detail, referring by numerals to the accompanying drawing forming a part of this application, in which:—

Fig. 1 is a fragmentary perspective view illustrating the method of using my improved clip looking toward the face of the work opposite that on which the operations actually take place in mounting or assembling the clips.

Fig. 2 is a perspective view of one form of clip with a portion of the body broken away.

Fig. 3 is a similar view of another form of clip.

Fig. 4 is a perspective view of two coacting clips showing plainly the interlocking engagement and illustrating in dotted lines

the manner in which the body of one clip is inserted in the socket.

Fig. 5 is a cross section of Fig. 1.

In carrying out my invention as herein embodied, 6 represents a furring bar, stud, joist or other support, it being understood that a number of these are used in suitably spaced relation for disposition of the open mesh lathing or foraminous plaster key in a manner to properly support the load. Disposed across the support 6 is the foraminous plaster key or metal lathing of woven wire, expanded metal or other open mesh structure 7.

The lathing or foraminous plaster key is first attached to the support 6 by means of light gauge tying wire. There are but few of these used and the purpose in particular is to line up the sheets and it is known as "sticking the lath".

After the lath is temporarily tied against the supports as above mentioned, clipping off may be started at any place along the line of supports by the use of either of the clips 8 shown in Figs. 2 or 9 shown in Fig. 3. Each 65 of the above clips includes a relatively long thin body 10, one end of which is bent or fashioned to provide a substantially U-shaped or open ended socket or saddle 11 and the point of connection between the socket and body is 70 known as a shoulder 12.

From one part of the socket or saddle 11 projects a strand 13 which extends beyond the open end of the said socket, as shown in Figs. 2 and 3 above said socket and this strand is 75 then bent at right angles away from the body 9 providing the bridge strand 14 and the latter is then bent at right angles to provide the free depending leg 15 parallel to the strand 13 and spaced therefrom a distance 80 equal to the width of the usual furring bars or supports. Under some conditions, as will be hereinafter set forth, it is desirable that the depending leg 15 be provided with a locking toe in which case a portion of said leg 15 is 85 bent back parallel with the body 10 to form the locking toe 16, shown in Fig. 2. As plainly shown in Figs. 2 and 3, the U-shaped holder formed by the strands 13 and 14 and the leg 15 is in the same plane as the socket or 90

100

saddle 11 and both are to one side of the body 9 with said socket between the body and the U-shaped holder.

Where the support 6 is of sufficient cross sectional area to prevent turning of the clip after the same is mounted in place, the locking toe 16 may be dispensed with. In assembling or mounting the clips, the leg 15 of one clip is first inserted through the meshes 5 of the lathing and said clip is then turned in corkscrew fashion until the U-shaped holder passes over the rear part of the support after which the body of the clip is moved or swung into engagement with the outer face 10 of the lath, as shown at the bottom or left hand end of Fig. 1. This action then brings the leg 15 to a position on the side of the support opposite that to which it entered the lath. The body of said clip is then fastened 15 in place by a suitable tie 17, such as a tie wire, passed about the support 6 and the body of said clip.

Another clip is then similarly mounted and when the body of said second clip is 20 moved or swung into contact with the lath, said body is forced, as by a blow from a pair of pliers over the shoulder 12 of the adjacent or coacting clip causing the lath to flex sufficiently to permit the body of the 25 second clip to pass between the lathing and the shoulder 12 of the adjacent clip for entrance into the open ended socket or saddle 11. When in place the bodies of the clips which are raised in the sockets are prevented 30 from becoming accidentally displaced because of the difficulty in forcing back the lathing a sufficient distance to carry the body over the shoulder. By reference to Fig. 4, it will be plainly apparent how the body 35 of one clip is forced over the shoulder of the adjacent clip just prior to being seated in the socket.

Where the clips are used on supports of relatively small cross sectional area, the locking toe 16 is utilized and after the U-shaped holder is placed over the support, said toe is forced over the lathing so as to engage the 40 face of said lathing opposite that which lies against the support and then when the body 45 is moved or swung into engagement with the lathing, said locking toe will be held so as to prevent the clip from turning on the support.

By actual practice, to assemble or install 50 clips as herein described, it becomes unnecessary to tie any but the first of a series of clips as the others are all securely locked by coaction with the sockets and co-operating parts of the lathing and since the body 55 of a succeeding clip is forced sidewise into the socket of the preceding clip, it is unnecessary to have any "play" for the U-shaped holder on the support nor is it necessary to deform the body for insertion in the socket.

Further, the use of clips of this kind have

the advantage of supporting the lathing over the entire or one hundred per cent of the surface of the supports.

Of course I do not wish to be limited to the exact details of construction as herein shown, 70 as these may be varied within the limits of the appended claims without departing from the spirit of my invention.

Having thus fully described my invention, 75 what I claim as new and useful is:—

1. The combination of a support, foraminous plaster key disposed across said support, a plurality of clips, each including a U-shaped holder for passage through the foraminous key and disposition about the support, an open-end socket to one side of the U-shaped holder, and a body projecting from 80 said socket, the body of each succeeding clip registering with the socket of the preceding clip after being forced between the body of 85 said preceding clip and the foraminous plaster key.

2. The structure set forth in claim 1 in combination with a locking toe projecting 90 from the U-shaped holder at the side opposite the socket and adapted to engage a portion of the foraminous plaster key opposite that portion of said foraminous plaster in contact with the support.

3. A clip produced from a strip of material fashioned to provide a U-shaped holder, an open ended socket beside said holder, and a body projecting from said socket, the point of connection between the socket and body 100 producing a shoulder.

4. A clip including a long body, a socket at one end of said body, a holder beside said socket, said body adapted to lie against the surface of lathing opposite the surface engaging a support with the holder projecting 105 through the lathing and partially surrounding the support and the open end of the socket, lying toward the lathing to receive the body of a succeeding clip after the same has been forced between the lathing and the shoulder formed at the point of connection 110 between the body and socket.

In testimony whereof I have hereunto affixed my signature.

JOHN S. RAYNOR. 115
